UNITED STATES PATENT OFFICE

EDGAR B. SYMONS, OF HOLLYWOOD, CALIFORNIA, ASSIGNOR TO NORDBERG MANUFACTURING COMPANY, OF MILWAUKEE, WISCONSIN, A CORPORATION OF WISCONSIN

CRUSHING MACHINE

Application filed February 20, 1929. Serial No. 341,336.

My invention relates to a crushing device, and particularly to an improvement in crushing devices in which a cone is gyrated in a normally fixed concave or bowl.

5 One object of my invention is to provide a bowl, and supporting means therefor, which shall be normally maintained in fixed position but which shall be adapted to yield to a predetermined pressure in excess of normal 10 crushing pressure or to permit the passage through the space between cone and bowl of uncrushable material. Another object is the provision of improved yielding means or 15 members whereby this yielding is permitted.

20 Another object is to provide an improved lubricating means and dust preventing means for a cone crusher of the type described. Other objects will appear from time to time 25 in the course of the specification and claims.

20 Certain of the material shown in the present application has been divided therefrom and is claimed in the co-pending divisional application 467,237, filed on July 11, 1930. This divided material includes the employment 25 of individual sets of springs as shown for example in Figures 2, 3 and 4, and the screw-threaded adjustment shown herein in Figure 1.

20 I illustrate my invention more or less diagrammatically in the accompanying drawings, wherein—

Figure 1 is a vertical axial section;

Figure 2 is a horizontal section on the line 2—2 of Figure 1; and

25 Figures 3 and 4 are partial horizontal sections through variant forms of my device.

Like parts are indicated by like symbols throughout the specification and drawings.

Referring to the drawings, A generally 40 indicates the main frame of a crushing device which may be formed at the bottom of any suitable base A¹, secured to a supporting surface, for example by the bolts A².

A main frame section is shown, as in Figure 2, as cylindrical in cross-section. It is 45 illustrated as terminating at its upper edge in a flange B, the top of which is inwardly beveled as at B¹ and outwardly beveled as at B² to receive the upper frame section or ring,

50 generally indicated as C. The flange B pro-

jects outwardly from the body A of the frame. Or, stating it otherwise, the body or frame A is recessed within the outer periphery of the flange B. The purpose of this recessing or offset will later appear. The member C is provided with a laterally extending flange or flanges C¹, outwardly extending from the generally cylindrical portion C², the cylindrical portion being inwardly screw-threaded as at C³. The flange or flanges C¹ 55 are provided with the beveled surfaces C⁴ and C⁵, opposed to the beveled surfaces B¹ and B² of the portion B.

The member B is apertured to receive a plurality of aligning members, indicated as the pins D, with the flanges D¹ and the upwardly projecting portions D² shown as slightly tapered and rounded at the tip.

Positioned about the main frame A are a plurality of groups of springs E. The tops and bottoms of said springs are compressed between a plurality of sets of abutment members or segments, an upper abutment E¹ and a lower abutment E² being provided for each set of springs E. While I do not wish to be limited to any particular number or arrangement of springs, I have indicated, in Figure 2, as a practical arrangement, a plurality of sets of springs, five springs to a set, the springs being arranged in staggered relation with three springs arranged in an arc adjacent the face of the main frame and two springs positioned more distantly therefrom. In order to maintain the compression of the springs and to provide a bond between the lower abutment E² and the member C¹, I employ a plurality of bolts E³ for each set of springs, said bolts being held at the top as at E⁴ and being provided at the bottom with locking and adjusting nuts E⁵, whereby the compression of the springs may be controlled. As an illustration, I have indicated three such bolts E³ for each group of springs, two of said bolts being aligned with surrounding 85 springs.

The member D serves to center the other of said springs, and it will be understood that, where necessary, axial lugs or plugs, such as E⁶, are employed to maintain the 100

springs properly aligned. E^7 indicates an outer rim about each such abutment member E^1 or E^2 . It will be observed, as in Figure 1, that the effect of the spring assembly will be to draw the flange or ring C^1 downwardly against the flange or ring B , and to maintain the frame portion C^2 fixed in position in relation to the frame A .

In screw-threaded relation to the spring C^2 is the bowl or concave supporting frame, generally indicated as G . It includes the cylindrical outer frame portion G^1 , screw-threaded as at G^2 in opposition to the screw-threaded portion C^3 of the member C^2 . It will be understood that rotation of the member G^1 in relation to the member C raises and lowers the bowl or concave, the means for effecting such rotation and adjustment being not indicated herein, since they form of themselves no part of the present invention. Inwardly and upwardly projecting from the lower edge of the member G^1 is the bowl support G^3 , which is connected to the outer portion G^1 as by the webs G^4 . The portion G^3 is apertured as at G^5 to permit the passage of securing lugs G^7 upon the bowl proper G^6 . G^8 indicate any suitable locking means whereby, by engagement with the lugs G^7 , the bowl G^6 can be brought up against the member G^3 . The details of these locking means are not described with greater fullness herein, being the subject of a co-pending application, No. 310,988 filed on the 8th day of October, 1928.

Positioned upon the top of the member C^2 is a member, generally indicated as H . It includes a cylindrical portion H^1 and a generally horizontal top portion H^2 , in which are formed a plurality of apertured bosses H^3 , which receive the heads H^4 of the bolts H^5 . H^6 is a nut upon said bolt, adapted to engage the lateral flanges or projections H^7 which is associated with the member G , whereby the tightening of the bolt H^5 will draw the member H downwardly against the upper edge of the frame member C^2 , or rather, will raise the member G , in relation to C^2 . It will be understood that the members H^7 project into pockets in the member H , whereby relative rotation of the members G and H is prevented.

Positioned within the inner periphery of the portion H^2 of the housing H is a cylindrical member J , within which is a hopper formed of segments J^1 resting upon a hopper shaped supporting surface J^2 , which in turn is secured to the upper edge of the portion G^3 , as by the bolts J^4 . The details of this hopper structure do not, of themselves, form a part of the present invention and will not be further considered. The ring J^5 may be employed to engage the tops of the segments J^1 , to hold them in position, the ring J^5 being held by the straps or abutments J^6 bolted as at J^7 to the upper edge of the

ring J . A wiping member J^8 is provided intermediate the ring J and the housing H .

K generally indicates a generally cylindrical bearing sleeve associated with the main frame A and lying in the vertical axis thereof. Positioned therewithin is the eccentrically apertured sleeve K^1 , associated with the gear K^2 , which, meshing with the driving gear K^3 , may be rotated from any suitable power source not herein shown. The crushing shaft K^4 penetrates the eccentric aperture K^5 of the sleeve K^1 and is gyrated in response to the rotation of said sleeve.

L generally indicates the bearing and guard member positioned above the sleeve K . It is indicated as having an upper spherical bearing surface L^1 , and is surrounded by the oil sump or peripheral passage L^2 , in which flows any suitable oil, discharge passage L^3 is in communication with the space formed by the gear box K^10 about the gear K^2 . L^4 indicates a flange extending outwardly from the sump L^2 and having an upper spherical bearing surface L^5 and a lower spherical bearing surface L^6 , both said surfaces being preferably concentric with the main spherical bearing surface L^1 . L^7 indicates an oil groove in the face of the surface L^5 , provided with passages L^8 extending to the bottom of the oil sump.

M generally indicates a cone mounted on the upper end of the shaft K^4 and is provided with a spherical bearing surface M^1 , conforming to and resting upon the surface L^1 . M^2 indicates an axial oil passage in the shaft K^4 , which is in communication with the lateral passage M^3 with the oil induct M^4 extending to the lower bearing surface M^1 . It there communicates with the circumferential oil passage M^5 , which in turn communicates with the radial passage M^6 extending to the wall of the shaft K^4 , and being adapted to deliver oil downwardly along said shaft to the gear box K^10 or to the bearing surface between shaft and eccentric sleeve. The crushing head M is provided with the outer conic surface portion, generally indicated as M^7 , and terminating at its lower edge in the downwardly extending apron M^8 .

M^9 indicates an inner apron positioned exteriorly of the surface M^1 . The members M^8 and M^9 have opposed parallel surfaces, indicated as M^{10} and M^{11} , within which slides the oil wiping member generally indicated as O , and having the flange O^1 and a spherical bearing surface opposed to the surface L^5 and a lower flange O^2 opposed to the surface L^6 . Any suitable means, for example the springs O^3 , are employed for thrusting the member O downwardly and for maintaining its upper member O^1 closely opposed to the upper bearing surface L^5 of the member L^4 .

Positioned upon the head M^7 is any suitable mantle P , shown in conic form, with the

upwardly extending central hub or top portion P^1 adapted to be engaged by the annular abutment P^2 controlled by the lock nut P^3 screw-threaded, as at P^4 , to the upper screw-threaded extension K^1 of the shaft K^4 . The portion P^3 is provided at its upper end with an outwardly extending circumferential flange P^5 , upon which is positioned any suitable feed limiting or feeding plate P^6 . The 5 details whereby the lock nut P^3 is held against rotation, in such fashion that the mantle is clamped upon the cone, do not of themselves, form part of the present invention and need not be considered in detail.

10 It will be realized that whereas I have described and shown a practical and operative device, nevertheless many changes might be made in the size, shape, number and disposition of parts without departing from the 15 spirit of my invention. I therefore wish my drawings to be taken as, in a broad sense, illustrative and diagrammatic, rather than as limiting me to the specific features herein described and shown, except so far as I limit 20 myself by the language of the claims.

The use and operation of my invention are as follows:

The invention relates to an improvement in cone crushers of the type wherein a spring release is provided for the bowl. In the 30 larger size of crushers it is important that a sufficient number of springs be spaced about a bowl to hold it in position against all but excess crushing strains. I find it 35 desirable to arrange the springs in a plurality of groups and to arrange the springs in each group at varying distances from the axis of the machine. These groups of springs are of sufficient power to hold the ring C^1 40 clamped firmly downwardly against the top of the frame A . On the other hand, if un-crushable material, such as tramp iron or caked stone, passes through the device, the 45 springs are of such strength and set at such compression as to give sufficiently to prevent breakage or stoppage of the machine and to pass the troublesome substance or body. When the bowl and its support tilt upwardly to permit the passage of such material, the 50 member C^1 is lifted from the member B . The bolts E^8 tend to maintain the alignment of the devices, but I prefer to employ, also, the pin or aligning members D , the upper ends 55 D^1 of which insure that the member C^1 will not escape from its proper alignment and will not rotate in relation to the member B . Such rotation, of course, throws a strain upon the bolts and springs.

Whereas I have described and shown a 60 particular arrangement of springs in groups it will be understood that I do not wish to be limited specifically to it, except so far as I do limit myself in my claims and in particular I may employ a concentric arrangement of springs, two or more springs being

positioned about the individual guides or bolts E^3 or about the members E^6 , as shown in Figures 3 and 4. I have indicated in Figure 3 a form of my device in which I employ the inner spring R and the outer spring R^1 about 70 each bolt or abutment. In the form of Figure 4 I illustrate a third external spring R^2 , about the other two. It will be realized that whereas I have illustrated these multiple springs as shown in connection with segments E^2 that they may be applied independently of such segments, with any suitable means for guiding and centering them or for grouping them, when they are arranged in groups. The group arrangement 75 is convenient but may not under all circumstances be necessary.

The member H is in effect a housing ring, and prevents the access of dust to the parts within it. It serves other primary purposes, however. The lateral projections H^7 , as above described, prevent any relative rotary movement of the member H and the member G . Therefore the ring H may act as a wrench for turning the bowl G within the ring C . Any suitable means for causing rotation of the ring H , such means being not shown herein in detail, have for effect to rotate the member G and to cause the member G to raise or lower within the screw-threaded ring C^2 . Assuming that the rotation is in such direction as to cause the member G to rise, it rises in relation to the member H which rests normally upon the top 90 of the member C^2 , upwardly projecting from the frame member C . The wiping member or washer J^8 provides a substantial dust proof connection between the inwardly projecting flange H^2 and the cylindrical member J about the hopper.

The bolts H^5 , with their nuts H^6 , serve to raise the member G , through the projections H^7 , to relieve the contact of the threads on the opposed members G^1 and C^2 . These threads are made with considerable play, and the act of crushing stone will lift the threads on the member G^2 and cause them to bind to the extent of the play between them and the opposed threads. It is in order to take up 110 this play that the bolts H are introduced. By tightening the bolts H after the correct setting has been obtained, the play is taken up, as to the loose threads. The nuts H^6 lift up on the bowl and the ring H exerts a downward pressure upon the top of the member C^2 .

The washers H^{10} may be made of fiber and may be interposed between steel washers, one above and one below. The washers H^{10} may for example be made of pieces of rubber belting. If a piece of steel goes through the 125 crushing cavity, it causes the ring C to be raised in relation to the member A , this tilting yielding release being important to prevent breakage of the device. As soon as the head recedes and the steel, or other uncrush-

able substance, as pass from the crushing cavity, there will be a pronounced blow when the ring member C seats itself on the frame as at C⁵. It is the function of the washers 5 H¹⁰ to absorb or cushion this shock. In practice they furnish sufficient pressure to keep the threads in contact, so that there will be no pounding but they give sufficiently to prevent stripping the threads on the bolts H⁵.
 10 The cone M is mounted upon a spherical bearing surface L¹, and this bearing surface is protected from the penetration of dust or the like, which would shortly wear it out, firstly by the circumferential oil sump and 15 secondly by the outer guard member L⁶ with its inner and outer spherical bearing surfaces in engagement with the inner and outer flanges of the dust guard member O.

The hopper above the cone is preferably 20 formed of a plurality of removable, and preferably separately removable segments J¹. These segments or liners are subjected to heavy wear and may be made of manganese 25 steel, being of course easily replaceable and being held in place for example upon the conic ring or supporting surface J², being held in position either by their form and interengagement, or by the rearward projections J¹⁰ which may project through the slots 30 J¹¹ of the member J². The ring J⁵ serves to hold them against upward movement.

I claim:

1. In a gyratory crusher, a circumferential frame member, a cone positioned within said 35 frame member and means for gyrating it, a bowl surrounding said cone and tiltably mounted upon said frame member, the plane of the tilting connection between bowl and frame intersecting said cone beneath its top.
 40 2. In a gyratory crusher, a circumferential frame member, a cone positioned within said frame member and means for gyrating it, a bowl surrounding said cone and tiltably mounted upon said frame member, the plane 45 of the tilting connection between bowl and frame intersection said cone beneath its top, and yielding means adapted normally to hold said bowl against movement in relation to said frame member.
 50 3. In a gyratory crusher, a cone and means for gyrating it, a bowl surrounding said cone, and a hopper positioned above said bowl, said hopper including a plurality of removable 55 segments.

4. In a gyratory crusher, a cone and means for gyrating it, a bowl surrounding said cone, and a hopper positioned above said bowl, said hopper including a plurality of removable 60 segments, and a generally cylindrical extension member positioned about the outer edge of said hopper.

5. In a gyratory crusher, a cone and means for gyrating it, a bowl surrounding said 65 cone, and a hopper positioned above said

bowl, said hopper including a plurality of separately removable segments.

6. In a gyratory crusher, a cone and means for gyrating it, a bowl surrounding said cone, and a hopper positioned above said bowl, 70 said hopper including a plurality of removable segments, and a conic supporting member upon which said segments rest.

7. In a gyratory crusher, a cone and means for gyrating it, a bowl surrounding said cone, 75 and a hopper positioned above said bowl, said hopper including a plurality of removable segments, and a conic supporting member upon which said segments rest, said supporting member being apertured, said segments being provided with securing members 80 adapted to penetrate such apertures.

8. In a gyratory crusher, a cone and means for gyrating it, a bowl surrounding said cone, and a hopper positioned above said bowl, 85 said hopper including a plurality of removable segments, and means for holding said segments in position.

9. In a gyratory crusher, a normally fixed circumferential frame member, a crushing cone positioned within said frame member and means for gyrating the cone, a bowl surrounding said cone and tiltably mounted upon said frame member, the plane of the tilting connection between bowl and frame 90 intersecting said cone beneath its top, and yielding means adapted normally to hold said bowl against movement in relation to said frame member.

Signed at Hollywood county of Los Angeles and State of California, this 1st day of February, 1929.

EDGAR B. SYMONS.
